(57) **CLAIM**

The ornamental design for a removable clip as shown and described.

DESCRIPTION

FIG. 1 is a top perspective view of a removable clip according to the invention;

FIG. 2 is a bottom perspective view of the removable clip of FIG. 1;

FIG. 3 is a top view of the removable clip of FIG. 1;

FIG. 4 is a bottom view of the removable clip of FIG. 1;

FIG. 5 is a front side view of the removable clip of FIG. 1;

FIG. 6 is a rear side view of the removable clip of FIG. 1;

FIG. 7 is a right side view of the removable clip of FIG. 1; and,

FIG. 8 is a left side view of the removable clip of FIG. 1.

Portions of the removable clip shown in broken lines form no part of the claimed design.

1 Claim, 8 Drawing Sheets
